UNITED STATES PATENT OFFICE

WILLIAM J. WOOLLEY, OF CHICAGO, ILLINOIS

OVERFLOW AND WASTE VALVE

Application filed March 14, 1929. Serial No. 346,903.

This invention relates in general to overflow valves which are adapted to be used as an overflow and drain valve in connection with bath tubs, wash basins, sinks and laundry trays, or vessels of a similar nature.

One of the objects of my invention is to provide an upright tubular drain valve and overflow pipe which is adapted to be raised and lowered, and twisted or rotated, and to provide means which is adapted to oscillate or rotate the valve on its seat previous to raising the valve to permit the waste to flow through the drain outlet.

Another object of my invention is to provide means for scouring and keeping the valve and valve seat faces clean to maintain a non-leakable waste or drain valve.

Another important object of my invention is to provide means for securing various positions of adjustment of the valve operating mechanism so as to correspond to the relative position of the drain valve and its corresponding seat.

A further important object of my invention is to provide means whereby the drain valve and overflow pipe operating mechanism and its mounting plate may be detachably secured in its various positions of adjustments to correspond to the said valve and its place of location, independent of the overflow and waste valve assembly.

Numerous other objects and advantages of the invention will be apparent as it is better understood from the following description, which, taken in connection with the accompanying drawings, discloses a preferred embodiment thereof.

Referring to the drawings:

Figure 1 is a sectional view of a structure embodying my invention, taken on a vertical plane centrally through the drain and overflow outlet of a bath tub or wash basin, only a portion of the tub being shown;

Fig. 2 is a section taken on the line 2-2 of Fig. 1, showing the manner of securing the tubular valve and overflow pipe to the valve operating mechanism, the tub or basin being omitted;

Fig. 3 is a section taken on line 3-3 of Fig. 1, showing the means for securing the

perforated valve operating mechanism mounting plate, the tub or basin being omitted;

Fig. 4 is a section taken on line 4-4 of Fig. 2 (the valve and valve operating mechanism being omitted) showing the manner in which the valve casing, the casing clamping plate, the tub or basin, and the valve operating mechanism mounting plate are detachably secured to each other;

Fig. 5 is a section taken on line 5-5 of Fig. 4, and shows one position of adjustment of the valve operating mechanism mounting plate with respect to that of the valve casing clamping plate;

Fig. 6 is a section taken on line 6-6 of Fig. 2, showing the manner in which the valve and valve operating mechanism, the valve casing and its clamping plate, the tub or basin, and the valve operating mechanism mounting plate are each, respectively, detachably secured to each other;

Fig. 7 is a similar view to that of Fig. 5, but showing the valve operating mechanism mounting plate in a central position of adjustment with respect to that of the valve casing clamping plate; and

Fig. 8 is a similar view to that of Fig. 4, but showing the valve operating mechanism mounting plate in another position of adjustment with respect to that of the valve casing clamping plate, or similar to the adjustment thereof, as indicated in light broken lines in Fig. 5.

Referring to Fig. 1, there will be seen a portion of a tub or basin 9 having a waste outlet or drain 10 and an overflow outlet 11. In the drain outlet pipe casing 12 is provided a valve seat 13 and seated thereon is an upright tubular drain valve and overflow pipe 14, having a circular valve 15 at its lower end. Connecting the overflow outlet 11 with that of the drain outlet casing 12 is a casing 16, which acts as a guide for the overflow pipe 14. In the upper end of the overflow pipe 14 is an elongated vertical hole or slot 17 and through the slot 17 is inserted a drain valve rotating and elevating means or crank 18. The shank 19 of the crank 18 is mounted for rotation in the hub 20 of a valve operat-

ing mechanism mounting plate 21. Holes 22 are provided in the said plate 21 as an overflow outlet.

The shank 19 is provided with a crank operating handle 23 and also a tension spring 24, which is adapted to keep the crank 18 in operative engagement with the slotted hole 17. By referring to Figs. 1, 2 and 6, it will be seen that any slight movement of the crank 18 will cause the tubular valve and overflow pipe 14 to rotate while it rests on its seat 13, causing a rubbing or scouring motion of the face of the valve 15 against the valve seat 13. As a result of the rubbing of the valve faces together, a non-leakable drain valve is maintained. To open the drain valve 15, the crank 18 is revolved until it engages the upper part of the slot 17, and, on continuing with the crank 18 the tubular valve and overflow pipe 14 is caused to rise until it and the crank and valve operating handle 23 are in the position as indicated by light dotted lines shown in Figs. 1 and 2, as 14', 15', 18' and 23'.

A drain outlet pipe 25 and the casing 16 are adjustably secured to the casing 12 by means of packing units 26. The drain pipe 25 is secured to a drain fitting 27, as shown in Fig. 1, and the fitting 27 is secured at the drain outlet in the usual manner to form a leak-proof joint.

The upper end of the casing 16 is secured in a fitting 28, in the manner indicated in Figs. 1, 2 and 4. Having secured the correct adjustment of the casing 16 and fitting 28 with respect to the overflow outlet 11, a rubber gasket 29 is inserted between the face of the fitting 28, and wall 9' of a tub or basin 9 and is there secured by means of a clamping plate 30 and hollow tapped screws 31 in the manner clearly indicated in Figs. 4 and 6. Having secured the fitting 28 to correspond with the opening 11, the valve operating mechanism mounting plate 21, having the valve operating mechanism mounted therein, may now be secured in place by means of screws 32, in the manner shown in Figs. 1, 4 and 6. In cases where the slot 17 may not suit the present adjustment of the valve operating mechanism or, owing to a lower position of the valve seat 13, would result in a lower position of the slot 17, means of readjustment is provided whereby the valve operating mechanism mounting plate 21 may be readjusted so that the valve operating mechanism or crank 18 will correspond with the lower position of the slot 17. That is, when the mounting plate 21 is lowered to the position as indicated by the light dotted lines 21', and the position of the screws 32 (as seen in Fig. 5, or as indicated in Fig. 8) or the plate 21 adjusted to the position indicated in Fig. 7, it carries the valve operating mechanism or crank 18 to a position which will correspond to such lower position in which the slot 17 may be.

It is thought that the invention and many of

its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In combined overflow and drain valves in combination with overflow and drain outlets of tubs, basins, vessels, and the like, having a drain-valve seat and an overflow outlet in common, of an upright tubular rotating and elevating drain valve and overflow pipe, and an adjustably mounted drain valve rotating and elevating mechanism detachably secured in the upper end of the said drain valve overflow pipe, means to secure a varied adjustment of the said valve rotating and elevating mechanism and means to vary the adjustment thereof.

2. In combined overflow and drain valves in combination with overflow and drain outlets of tubs, basins, vessels, and the like, having a drain-valve seat and an overflow outlet in common, of an upright tubular rotating and elevating drain valve and overflow pipe, an adjustably mounted drain valve rotating and elevating mechanism detachably secured in the upper end of the said drain valve overflow pipe, the said valve operating mechanism being rotatably mounted in a valve adjustment plate variably adjustably secured against the side of the tub, basin, or the like, at its overflow outlet, and overflow openings in the said mounting plate, the said adjustment plate being detachably secured in the drain valve overflow pipe casing, a handle detachably secured to the said mechanism, and a tension spring to secure the said handle against the said mounting plate.

3. In combined overflow and drain valves in combination with overflow and drain outlets of tubs, basins, vessels, and the like, having a drain-valve seat and an overflow outlet in common, of an upright tubular rotating and elevating drain valve and overflow pipe, and an adjustably mounted drain valve rotating and elevating mechanism detachably secured in the upper end of the said drain valve overflow pipe, a vertically slotted opening in the upper end of said drain valve overflow pipe, a drain valve overflow pipe rotating and elevating means formed in the said mechanism comprising a crank, said crank being adapted to be detachably secured in the said slotted opening.

4. In combined overflow and drain valves in combination with overflow and drain outlets of tubs, basins, and the like, having a drain-valve seat and an overflow outlet in common, of an upright tubular rotatable and

raisable drain valve and overflow pipe, and an adjustably mounted drain valve rotating and elevating mechanism detachably secured in the upper end of the said drain valve overflow pipe, a casing forming a guide for the said valve and overflow pipe and a connection to the drain outlet, and means to adjustably connect the said casing and the drain outlet together, a clamping plate adapted as a means to secure the said casing to the tub, basin, or the like, at its overflow outlet, and hollow screws for securing the said casing, the clamping plate, and the tub, or basin, together.

5. In combined overflow and drain valves in combination with overflow and drain outlets of tubs, basins, and the like, having a drain-valve seat and an overflow outlet in common, of an upright tubular rotatable and raisable drain valve and overflow pipe, and an adjustably mounted drain valve rotating and elevating mechanism detachably secured in a vertical slot in the upper end of the said drain valve overflow pipe, a casing forming 25 a guide for the said valve and overflow pipe, a clamping plate and a set of hollow screws adapted as a means to secure the said casing to the tub, or basin, a set of screw-holes in the said casing together with said hollow screws adapted as a means to secure a varied adjustment of the said drain valve and overflow pipe operating mechanism, a perforated mounting plate for said operating mechanism adapted to be detachably secured in various 35 positions of adjustment by means of a set of screws secured in the said screw-holes.

6. A combined overflow and drain valve for the overflow and drain outlets of bath fixtures having a drain-valve seat, comprising 40 an upright tubular drain valve and overflow pipe providing a circular drain valve at its lower end and adapted to be raised and lowered to open and close the drain outlet, and mechanism for raising and lowering and 45 rotating the said valve, said mechanism being adjustably mounted at the overflow outlet of the tub and adjustably attached to the upper end of said tubular valve.

7. A combined overflow and drain valve 50 for overflow and drain outlets of bath fixtures, having a drain-valve seat, comprising an upright tubular self-scouring drain valve and overflow pipe for keeping the drain valve seats clean, drain valve operating mechanism adjustably mounted at the overflow 55 of the bath fixture, and means to adjust the said valve operating mechanism with respect to the valve adjustment.

8. A combined overflow and drain valve 60 for overflow and drain outlets of tubs, basins, vessels, and the like, having a drain-valve seat, comprising an upright tubular oscillatable drain valve and overflow pipe, and drain-valve operating mechanism detachably 65 secured to the upper end of the said drain-

valve overflow pipe for oscillating said drain valve on its seat before unseating the valve.

9. A combined overflow and drain valve for overflow and drain outlets of tubs, basins, vessels, and the like, having a drain-valve seat, comprising an upright tubular drain valve and overflow pipe, drain-valve operating mechanism detachably secured to the upper end of the said drain-valve overflow pipe for elevating and oscillating said drain valve, and valve control means to rotate before unseating said valve.

10. A combined overflow and drain valve for overflow and drain outlets of bath fixtures, having a drain-valve seat, comprising an upright tubular drain valve and overflow pipe, and an adjustably mounted drain-valve operating mechanism detachably secured in the upper end of the said drain-valve overflow pipe for rotating and elevating said drain valve, and control means to rotate the said valve before and while raising it from its seat to keep the valve seat clean.
